UNITED STATES PATENT OFFICE.

JAMES HASCALL, OF HANNIBAL, MISSOURI.

FENCE-CLAMP.

1,219,395.

Specification of Letters Patent. Patented Mar. 13, 1917.

Application filed October 20, 1916. Serial No. 126,746.

To all whom it may concern:

Be it known that I, JAMES HASCALL, a citizen of the United States, residing at Hannibal, in the county of Marion and State 5 of Missouri, have invented new and useful Improvements in Fence-Clamps, of which the following is a specification.

This invention relates to fence clamps which are used for the purpose of clamping 10 and holding wire fence fabric for the purpose of stretching the same to hold it in tight condition while being nailed upon or otherwise connected with the fence posts.

The invention has for its object to produce 15 a simple and improved clamp which may be readily applied to the fence fabric and which will be so constructed that strain exerted on the clamp in the proper direction will tend to increase the grip thereof on the wire 20 fabric.

A further object of the invention is to produce a clamping device of simple and improved construction including a pair of jaws that are separably connected together, said 25 jaws being detachably connected with a toggle device with which the draft strain is connected in such a fashion as to draw the clamps tightly in the direction of each other to engage the fabric inserted therebetween.

30 A further object of the invention is to simplify and improve the construction and arrangement of the detailed parts of the device.

With these and other ends in view which 35 will readily appear as the nature of the invention is better understood, the same consists in the improved construction and novel arrangement and combination of parts which will be hereinafter fully described and particularly pointed out in the claims.

In the accompanying drawings has been 40 illustrated a simple and preferred form of the invention, it being, however, understood that no limitation is necessarily made to the precise structural details therein exhibited, but that changes, alterations and modifications within the scope of the claims may be resorted to when desired.

In the drawings,—

45 Figure 1 is a perspective view showing the improved clamp arranged in position for operation.

Fig. 2 is a plan view.

50 Fig. 3 is a sectional view taken on the line 3—3 in Fig. 2.

Fig. 4 is a horizontal sectional view taken on the line 4—4 in Fig. 3.

Fig. 5 is a view in side elevation of one of the clamping jaws and the clamping bar carried thereby.

Corresponding parts in the several figures are denoted by like characters of reference.

The clamping jaws 15 which have been shown as being of approximately rectangular shape are provided at one end thereof 55 with interengaging hinge lugs 16 for the passage of a pintle or pivot member 17 whereby the said jaws are pivotally connected together. The jaws are provided in their opposed faces with rectangular recesses 18 of proper dimensions to receive a clamping bar 19, said bar consisting preferably of a piece of 2 by 4 inch scantling of proper length, it being understood that the length of the clamping bars shall be about equal to the 70 width of the fence material in connection with which the device is to be used, and preferably of a length somewhat exceeding the width of the fence material. The clamping bars may be secured in the recesses of the 75 respective jaws by means of screws 20 or by fastening members of any description. The clamping bars are also provided on their opposed faces with interengaging strips 21 of steel or other suitable material, said strips 80 being preferably slightly inset in the face of the clamping bars and secured by screws or other fastening means, the purpose of said strips being to crimp the wire fabric engaged thereby so that said fabric will be securely gripped by the clamping device.

85 Each jaw is provided at its outer corner, distant from the hinge lug 16, with a pair of projections 22, the outer faces of which are provided with notches or recesses 23 for the reception of a pin or pivot member 24 carried by a toggle link 25 which is inserted between the projections 22. The toggle links are pivotally connected with a head block 26, which latter carries a clevis 27 whereby 90 it may be connected with a source of power.

95 It will be seen from the foregoing that the toggle links are detachably connected with the clamping jaws by means of the pins 24 which loosely engage the recesses 23 in the projections 22. The clamping jaws may be separated from each other by simply removing the pintle or pivot member 17. When the jaws are thus separated they may 100 be arranged adjacent to opposite faces of the 110

wire fabric that is to be stretched, the lugs 16 being inserted through an opening in the fabric, after which the pintle or pivot member is replaced. By moving the jaws in the 5 direction of each other above the axis of the pivot member 17, the clamping bars will engage opposite sides of the fabric which will be crimped and held securely therebetween by the action of the strips 21. The toggle 10 links are now connected with the jaws by inserting the pins 24 in the recesses 23, after which by pulling on the head block 26, the jaws will become tightened on the fabric, and the latter will be placed under tensile 15 strain. It is obvious that power of any kind or description may be used for exerting the desired pull or tension on the head block; the clevis member may be connected with the end of a rope or cable leading to a wind- 20 lass operated manually or by animals, or animal power may be applied directly to the clevis. Lever or other power may also be employed when deemed desirable or expedient.

25 As will be seen from the foregoing description, the improved fence clamping device is extremely simple in its construction, and it is capable of being produced at a very moderate expense, the clamping jaws being 30 made, as well as the head block, preferably of cast iron, while the clamping bars are nothing more than pieces of ordinary scantling having metallic strips mounted on the faces thereof. Owing to its structure as 35 herein described, the clamping jaws may be very quickly disengaged and adjusted adjacent to opposite faces of the wire fabric that is to be stretched, and the general construction of the device is of such a nature as to

render it thoroughly effective for the purposes for which it is provided. 40

Having thus described the invention, what is claimed as new, is:—

1. In a fence clamp, a pair of jaws of substantially rectangular form having interengaging hinge lugs and a pivot member engaging the same, said jaws being provided at the outer corners of the free ends thereof with pairs of projections having recesses in their outer faces, a toggle device including a head block, and links pivotally connected therewith, said links extending between the projections and having transverse pins engaging the recesses in said projections, and a clevis member connected with the head 55 block, said clamping jaws being provided with recesses in the faces thereof and with clamping bars secured in said recesses. 50

2. In a fence clamp, a pair of jaws of substantially rectangular form having interengaging hinge lugs and a pivot member engaging the same, said jaws being provided at the outer corners of the free ends thereof with pairs of projections having recesses in their outer faces, a toggle device including a head block, and links pivotally connected therewith, said links extending between the projections and having transverse pins engaging the recesses in said projections, and a clevis member connected with the head 65 block, said clamping jaws being provided with recesses in the faces thereof and with clamping bars secured in said recesses, the 70 clamping bars having crimping strips inset in the faces thereof and extending longitudinally thereof. 75

In testimony whereof I affix my signature.
JAMES HASCALL.
